Inventor:

UNITED STATES PATENT OFFICE.

MORLEY PUNSHON REYNOLDS, OF CLEVELAND, OHIO, ASSIGNOR TO W. S. TYLER COMPANY, OF CLEVELAND, OHIO, A CORPORATION OF OHIO.

COLLECTOR.

1,082,766.

Specification of Letters Patent. Patented Dec. 30, 1913.

Application filed September 16, 1912. Serial No. 720,512.

To all whom it may concern:

Be it known that I, MORLEY PUNSHON REYNOLDS, a resident of Cleveland, in the county of Cuyahoga and State of Ohio, have 5 invented a new and useful Improvement in Collectors; and I do hereby declare the following to be a full, clear, and exact description thereof.

My invention relates to collectors and has 10 special reference to such devices for use in collecting material from gases, etc.

In the collecting of material, such as zinc 15 oxid, and such as is practical at the present time by the most approved method, the zinc 20 oxid as it comes from the smelter is passed into canvas bags, located in what is known as the "bag house," and such bags are of about 22" in diameter and formed in three 25 sections by two hoops within the same at suitable intervals so that each of said bags 30 is about thirteen feet long and suspended vertically in the regular manner. As the gas is projected into such bags the zinc oxid in such gas is caught on the interior of the 35 bag and retained there, while the gas passes out through the meshes in the bag, and about four times a day the gas is shut off from each bag so that the operator can shake such bag by grasping the same to allow the zinc 40 oxid on the inner sides of the same to drop therefrom through a funnel at the lower end of the bag and into an ordinary bag for handling, etc. In such method the bag when the gas is first put into the same will 45 allow some of the zinc oxid to pass through the meshes of the same as waste by reason of none or only a small amount of the zinc 50 oxid being on such bag as gradually collected, so that the oxid in such waste gas is lost or wasted, which in the parlance of this art is—the bag smokes, as such waste 55 oxid is somewhat gray in color, and such bags frequently get holes or rents within the same, which will also allow the zinc oxid, 60 to be wasted thereby and cause such smoking of the bag. The shaking of the bag is also very long, hard and laborious to procure the dropping of all the oxid collected 65 on the same on account of the operatives being compelled to start such shaking at the 70 top section of the bag by the use of their hands and then continue such shaking of the bag down to its lower end.

The object of my invention is to overcome

these objections and difficulties and to provide a cheap, simple and efficient collector, which can be operated automatically, and one in which there will be no waste of the zinc oxid or other material to be collected, so that all the material can be collected by 55 such collector.

To these ends my invention consists, generally stated, in the novel arrangement, construction and combination of parts as hereinafter more specifically set forth and described and particularly pointed out in the 60 claim.

To enable others skilled in the art to which my invention appertains to construct and use my improved collector, I will describe the same more fully referring to the 65 accompanying drawings, in which:—

Figure 1 is a vertical central section of my improved collector. Fig. 2 is a cross section of the same on the line 3—3 Fig. 1. Fig. 3 70 is a like section on the line 2—2 Fig. 1. Fig. 4 is an enlarged side view, partly in section of the lower end of the collector.

Like symbols of reference herein indicate like parts in each of the figures of the drawings.

As illustrated in the drawing A represents my improved collector which comprises an inner receptacle or bag 1 and an outer receptacle or bag 2, both of which are preferably circular in form with the outer bag 2 surrounding the inner bag 1, and forming a space 3 between the same. These bags 1 and 2 are suspended vertically in any suitable manner, such as from the beam *a* above 80 the same, while a shaft 4 is journaled in said beam, which shaft passes centrally through said bags and is journaled at its lower end in one of the steady bars 5 below said bags. The bags 1 and 2 are formed 85 from wire cloth or fabric of the desired mesh, such as is shown at 1' and 2', and such fabric is supported and strengthened by T-bars 7 exteriorly of the same and connected thereto. The upper end of the bag 1 90 has a sheet metal cover 8 extending over the same and connected thereto by a ring 9 of angle shape which is connected to the fabric 1' of said bag and interiorly of the same, and a like cover 8' and ring 9' is connected 95 to the upper end of the fabric 2' of the bag 2 and against a plate 10 of sheet metal between said ring and fabric for extending 100 105

down along said fabric a short distance and forming a ring. Extending around the lower end of each of the bags 1 and 2 respectively are ring plates 11 and 12, which are connected in any suitable manner to the fabrics 1' and 2' and bars 7 on the same, and extend up from the steadyng bars 5 along said fabrics for a short distance to form the bottomless compartments 13 and 14 in the bag 1 and between said bag and bag 2, respectively.

Secured to and extending out from the shaft 4 are the two arms 16, which are positioned within the bag 1, the upper arm being located adjacent to the upper end of the bag 1 and the lower arm being located adjacent to the lower end of such bag and above the compartment 13 in said bag and between the ends of each of said arms is a bar 17 carrying a brush 18. This brush 18 is preferably formed of metal such as wire, and the end of the same is adapted to engage with the wire fabric 1' of the bag 1 between the upper end of said bag and the lower end of the same adjacent to said compartment 13.

Above the bag 1 and extending through the cover 8' on the bag 2 is the shaft 19, which extends loosely around the shaft 4 and has arms 20 secured thereto, by a central bearing 20' on said shaft. These arms 20 are positioned between the cover 8 on the bag 1 and cover 8' on the bag 2 and their ends terminate about midway of the space 3 between the fabrics 1' and 2' of said bags. A circular band 21' is connected to the ends of each of the arms 20 and a bar 21 is connected to the end of said arms 20 through said band. These bars 21 extend down and their lower ends are bifurcated for carrying a grooved wheel 22, which travels on a circular track 22' in the compartment 14 and supported on the steadyng bars 5. A brush 23, preferably formed of wire, is connected to one of the bars 21 and it extends from the ring plate 10 on the bag 2 down to the compartment 14 between said bag and bag 1.

A pinion 24 is secured to the shaft 4 above the bag 2 and shaft 19, and a pinion 25 on a shaft 25' engages with said pinion 24. A pinion 26 is also connected to the shaft 19 above the bag 2, and a pinion 27 on a shaft 27' engages with said pinion 26. Hand wheels 28 and 28' are connected to the shafts 25' and 27' respectively for operating the same to revolve the brushes 18 and 23, as hereinafter described, but if desired such shafts may be connected to any suitable source of power for being operated mechanically.

The use and operation of my improved collector is as follows: The zinc oxid gas as it comes from the smelter enters the bag 1 from a pipe α , which extends through the

compartment 13 and opens into said bag above said compartment, so that the zinc oxid in such gas is caught and retained on the inner face of the fabric 1' of said bag, while any waste gas passing through said fabric will come in contact with fabric 2' of the bag 2 and thus catch and retain the zinc oxid in such waste gas on the inner face of said fabric 2, while all the waste gases will pass through the meshes of said bags and escape into the atmosphere. When a sufficient amount of the zinc oxid has been collected on the inner faces of the fabrics 1' and 2' of the bags 1 and 2, respectively, particularly the fabric 1', and it is desired to remove the same, all that is necessary is to revolve the brush 18 in the bag 1 by means of the shaft 25' and pinions 24 and 25 connected thereto and to the shaft 4, which will allow said brush in its rotation around and within said bag to clean off and remove all the zinc oxid collected on the fabric 1' of the bag 1 to thereby permit such material to drop down through the compartment 13 and thence through the steadyng bars 5 and usual funnel b employed under the same into the usual bag under the pipe c connected to said funnel for handling or storage under said funnel. After this is done the zinc oxid gas continues flowing into the bag 1, and after sufficient interval to thinly cover bag 1 with oxid, and the brush 23 in the bag 2 is revolved by means of the shaft 27', and pinions 26 and 27 connected thereto and to the shaft 19, which will allow said brush in its rotation around and within said bag to clean off and remove all the zinc oxid collected on the fabric 2' of such bag to thus permit such material to drop down through the compartment 13 and thence through the steadyng bars 5 and funnel into the shipping or storing bag, as above described.

It will be evident that while the collected material is being removed, from the fabric 2' of the bag 2, as above described, such material is at the same time being collected on the fabric 1' of the bag 1, and during the removal of the material from the fabric 1' of the bag 1, the material is being collected on the fabric 2' of the bag, so that practically there will be no waste at any time in the operations of collecting the material or removing it from the device, while at the same time that the outer bag is being cleared of its collected material the inner bag is collecting such material.

If desired, any number of bags may be used having an inner bag for the gas to enter, then the next size over and around same and so on, with a space formed between such bags, also any number of brushes, as desired, may be used in the bags and made adjustable, while various other modifications and changes in the design, construction and application of my improved

collector may be resorted to without departing from the spirit of the invention or sacrificing any of its advantages.

It will thus be seen that my improved collector can be used for collecting material other than zinc oxid, as described, and there will be sufficient coating of the material left on the bags after cleaning to hold and readily take another coating, while at the same time there will be a great saving in the smoking of the bags so that there will be no loss of material from the waste gases. The device will have a greater capacity than the canvas bags by holding a greater amount of material as a coating, while the device will also be quicker and more convenient to operate than the use of canvas bags, and will be more labor saving and cheaper to handle, either in operating or being kept in repair.

What I claim as my invention and desire to secure by Letters-Patent is:—

A device for collecting ingredients from

gases comprising an inner annular receptacle of woven wire fabric for collecting the ingredients, an outer annular receptacle of woven wire fabric around the same for collecting the ingredients, said receptacles being in parallel line with each other and having a space formed between the same, revoluble means within the inner receptacle for moving the collected material therefrom, and revoluble means within said space and supported above said receptacles for removing the collected material from said outer receptacle, said last named means being adapted to travel on tracks at the lower end of the same.

In testimony whereof, I the said MORLEY PUNSHON REYNOLDS have hereunto set my hand.

MORLEY PUNSHON REYNOLDS.
